HOWARD JEROME McELVAIN, OF PORTLAND, OREGON, ASSIGNOR OF ONE-HALF TO
HOWARD C. McELVAIN, OF PORTLAND, OREGON

ROCK CRUSHER

Application filed April 24, 1930. Serial No. 448,942.

My invention is for use in the crushing and pulverizing of stone, ore, coal, and any and all substances where relatively coarse, hard material is to be reduced in size, and in commercial quantities. The invention may be classed as a modified gyratory crusher in that the frame and the jaws are of a form similar to that of the gyratory crusher, the primary difference being that the central wearing plates are moved substantially in a vertical reciprocating motion rather than having a gyratory motion imparted thereto. The device in its preferred embodiment consists of a frame made up of a plurality of parts removably secured together. A spider is disposed in the upper end of the frame having for its object the stiffening of the frame and the support of the upper end of the main or primary shaft. The lower end of the shaft is connected within a suitable bearing yoke to a countershaft to transform rotary motion into reciprocating motion. Through the action of an eccentric disposed upon the countershaft or driving shaft an up and down movement is imparted to the main shaft. Means are provided for the preventing of the entry of the crushed cominuted material into the main shaft bearings with suitable means being provided for the replacement of the upper and lower mantle comprising the movable jaw elements of the crusher and for the replacement of the concaves which in effect are the stationary jaws of the crusher. Suitable means are also provided through an adjustable bearing for regulating the spaced relation of the respective crusher jaws. The primary shaft to which the mantle, or movable jaws, are secured is preferably made having an enlarged central section to which the mantles may be removably secured.

One of the objects of my invention is to so construct a crusher that it will use a minimum of power and that will have a greater capacity than that of the conventional gyratory crusher.

A further object of my invention resides in a simplified construction and one composed of but few parts with simple means being provided for predetermining the length of stroke of the movable jaw elements and at the same time to provide simple means for the changing of the spaced relationship between the stationary jaws and the movable jaws of the crusher.

A still further object of my invention consists in providing a crusher wherein the crushing pressure is applied through the use of tension being applied upon the main or primary shaft.

A still further object of my invention consists in providing a countershaft structure having a single cam surface provided thereupon that is in registerable engagement with a yoke disposed between the countershaft and the main shaft disposed vertically within the frame.

A still further object of my invention consists in providing means that are easily adjustable through the manipulation of which the degree of fineness of the material to be crushed may be predetermined.

With these and incidental objects in view, the invention consists in certain novel features of construction and combination of parts, the essential elements of which are set forth in the appended claim, and a preferred form of embodiment of which is hereinafter shown with reference to the drawings which accompany and form a part of this specification.

In the drawings:

Fig. 1 is a side view of the assembled device.

Fig. 2 is a longitudinal, vertical, sectional, side view of the assembled device, the same being taken on line 2—2 of Fig. 1, looking in the direction indicated.

Fig. 3 is a cross section, plan view taken on line 3—3 of Fig. 2 looking in the direction indicated.

Fig. 4 is a fragmentary, sectional, side view

of the base portion of the device, the same being taken on line 4—4 of Fig. 3 looking in the direction indicated.

Fig. 5 is a fragmentary, sectional, plan view of the countershaft and of the yoke journaled thereupon, the same being taken on line 5—5 of Fig. 4 looking in the direction indicated.

Like reference characters refer to like parts throughout the several views.

I preferably form the frame of my device of a base section 1 and a top section 2, the base section having a peripheral flange 3 disposed about its upper section and the top section 2 having a flange 4 disposed about its base. The flanges 3 and 4 are in registerable alignment with each other through which fastening holes pass and through which any suitable means are provided for securing the frame sections together. A recess 5 is disposed within the upper surface of the base section and a ring 6 is formed upon the lower surface of the top section, the same being adapted to engage each other to strengthen the assembly. A spider 7 extends across the mouth of the crusher and is secured to the upper end of the crusher frame by any suitable fastening means as by bolts 8. A journal bearing 9 is placed within the base section of the frame with a suitable bearing hub 10 formed within the base portion of the frame. Cross spokes 11 connect the hub 10 with the side wall 12 of the base of the frame and are formed integral therewith. The main shaft 13 runs longitudinally of the frame, the same being slidably disposed within the bearing 9 and within the bearing 14 that is disposed central of the spider 7. A frustaconical section 15 is formed integral with the main shaft, the same being an inverted frustacone. A compressible element, as a coil spring 16, rests upon the upper surface of the spider upon its one end and engages the underside 17 of a placement cap 18 upon the other. The cap 18 is secured to the upper end of the shaft by any suitable means as by threaded members 19. A cross head, or yoke, 20 is journaled about a cross head pin 21 that is disposed and adequately supported within the lower end 50 of the primary shaft 13. A countershaft 22 is journaled within suitable bearings within the base portion of the frame and an eccentric 23 is formed within the central portion of the countershaft 22. The cross head, or yoke, 20 is journaled upon its one end to the countershaft 22 and upon its oppositely disposed end to the cross head pin 21. As the shaft 22 is rotated, an up and down movement, or oscillating movement, is imparted 60 to the main shaft 13. The countershaft 22 is journaled within suitable bearings disposed within the base of the machine. Shims 24 are provided within the bearing to facilitate the taking up of the bearing and to thereby 65 raise and lower the main shaft 13 relative to

the frame and to automatically increase or decrease the openings between the respective crushing surfaces of the frame and the movable crushing plates disposed upon the main shaft. The pillow blocks 25 are secured to the journal bearing by any suitable fastening means as by bolts 26. Removable upper and lower concave plates 27 and 28 are removably secured to the inside of the upper portion of the frame and the central crushing plates 29 are removably secured to the frustaconical section 15 of the primary shaft. Lugs are formed on the inner surface of the mantle plates 29, that are in registerable engagement with a recess formed within the outer surface of the frustaconical member 15 to eliminate a part of the strain that would be otherwise developed upon the fastening bolts 30. A protector shield block 31 is disposed about the upper end of the hub 10 and is in engagement with the outer surface of the main shaft. Suitable compressible washers 32 may be placed between the protector shield block 31 and the upper end of the hub 10 and the upper end of the bearing 9. The purpose of the same is to prevent gritty material from entering, as much as possible, the bearing surfaces disposed between the main shaft and the bearing 9. A lubricating hole 33 extends through the side wall of the base of the frame and through the arms or spokes 11 and through the bearing 9. A pressure is built up within the bearing by a lubricator 34 that is disposed at a higher elevation than the upper surface of the hub 10 and the bearing 9 in order to lubricate the same. To reduce the weight of the elements placed above the cross head, or yoke 20, the main shaft, and especially the frustaconical portion of the same, may be made hollow. A shield 35 is placed upon the spider 7 and about the shaft to prevent foreign material from getting into the bearing 14 and the wearing surface of the shaft. Discharge spouts 36 are provided through the side walls of the base of the frame for liberating the crushed material being developed by the crusher. A base flange 37 is disposed about the lower surface of the base of the frame for supporting the same.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claim which follows.

What I claim is:

In a device of the class described, the combination of a main frame composed of upper and lower sections fabricated together, a cross yoke removably secured to the upper end of the frame, a main shaft reciprocably disposed within bearings that are in axial alignment

with each other that are removably secured to a hub disposed within the base of the frame and to the cross yoke, the bearings being in axial alignment with each other, a placement 5 cap removably secured to the upper end of the main shaft and a compressible element disposed between the cross yoke and the placement cap, means for imparting an up and down movement to the main shaft, sets of 10 wearing plates disposed in spaced relationship with each other disposed within the upper portion of the frame and about the shaft, and means for predetermining the spaced relationship of the respective pairs of plates.
